DESIGN FOR A MASTER COUPLING SPANNER BARREL TAP AND ROD WRENCH COM- BINATION TOOL

Bernard Czekalski, Hazleton, Pa.

Application July 5, 1944, Serial No. 114,315

Term of patent 14 years

(Cl. D54—16)

To all whom it may concern:

Be it known that I, Bernard Czekalski, a citizen of the United States of America, residing at Hazleton, county of Luzerne, and State of Pennsylvania, have invented a new, original, and ornamental Design for a Master Coupling Spanner Barrel Tap and Rod Wrench Combination Tool, of which the following is a specification, reference being had to the accompanying drawing, forming a part thereof.

In the drawing:

Figure 1 is a detail side elevational view of a master coupling spanner barrel tap and rod

wrench combination tool embodying my new design.

Figure 2 is a bottom plan view of the same.

Figure 3 is a top plan view of the same.

Figure 4 is a detail front elevational view of the same, and

Figure 5 is a sectional view taken on the line 5—5 of Figure 1.

I claim:

The ornamental design for a master coupling spanner barrel tap and rod wrench combination tool, as shown.

BERNARD CZEKALSKI.
